UNITED STATES PATENT OFFICE.

WILLIAM C. BRIGHTLY, OF ENGLEWOOD, NEW JERSEY.

HYDRANT-WRENCH.

1,286,926.

Specification of Letters Patent. Patented Dec. 10, 1918.

Application filed December 18, 1913. Serial No. 807,425.

To all whom it may concern:

Be it known that I, WILLIAM C. BRIGHTLY, a citizen of the United States, and a resident of Englewood, in the county of Bergen and 5 State of New Jersey, have invented a new and Improved Hydrant-Wrench, of which the following is a full, clear, and exact description.

This invention relates to a hydrant wrench, 10 particularly of the self-adjusting type that is especially adapted for use by firemen to remove the caps of fire plugs and operate the valves thereof, although of course the invention can be adapted for other uses.

15 The invention has for its general objects to improve and simplify the construction and operation of wrenches of the character referred to so as to be reliable and efficient in use, comparatively inexpensive to manufacture, and so designed as to be easily and quickly applied to or removed from a nut and to be self-adjusting thereto as the wrench is turned to screw or unscrew the nut or equivalent part.

25 Another object of the invention is the provision of a wrench having a novel arrangement of head and nut encircling element pivotally mounted thereon in such a manner that the element and head will tightly grip 30 the nut to be screwed or unscrewed, the gripping or releasing of the nut being effected by a slight turning movement of the handle or element.

With such objects in view, and others 35 which will appear as the description proceeds, the invention comprises various novel features of construction and arrangement of parts, such as will be set forth with particularity in the following description and 40 claims appended hereto.

In the accompanying drawing which illustrates certain embodiments of the invention, and wherein similar characters of reference indicate corresponding parts in all the 45 views,

Figure 1 is a perspective view of the wrench;

Fig. 2 is a side view thereof;

Fig. 3 is a view of the wrench with the 50 nut embracing element shown in different positions by full and broken lines to illustrate its use with nuts of different sizes; and

Fig. 4 is a sectional view showing a modified form of wrench.

55 Referring to the drawing, 1 designates the handle of the wrench; 2 the head thereof,

and 3 the nut embracing element. The head is composed of two spaced flat members α and α' between which the flattened portion b of the nut embracing member 3 extends, 60 there being a pivot 4 passing through the members α and α' of the head and the portion b of the element 3. This element 3 has an opening 5 for the reception of a nut, such opening having a plurality of angularly-disposed walls or surfaces 6 for engagement with two adjacent sides of the nut to be 65 screwed or unscrewed. The portion of the element 3 where these walls 6 are located is widened so as to be in total width equal to 70 or practically the same as the width of the head 2 in a direction parallel with the pivot 4. The pivot 4 is located at one side of the center line of the element 3, and the pivot is also eccentric to the curved surfaces 7 of the 75 members α and α' of the head, such surfaces 7 serving to engage the opposite side of the nut from the side with which the surfaces 6 engage. In the present instance the wrench is shown as suitable for pentagonal nuts, but 80 it is to be understood that the opening in the element 3 can be so formed that the wrench can be used on other non-parallel sided polygonal nuts.

In using the wrench the element 3 is 85 thrown in such a direction that its center line will be at the side of the center line of the handle on which the pivot 4 is located; or in other words, when the parts are in the position shown in Fig. 3, the element 3 will 90 be thrown to the left, so that a nut can be engaged in the opening 5 of the element 3. When this engagement is effected the handle 1 is moved in an anti-clockwise direction so as to bring the surfaces 7 of the head members of the handle into engagement with the nut, as clearly shown by the full lines, 95 Fig. 3. The surfaces 7 of the two members α and α' may be so curved that nuts of different sizes can be gripped by the wrench, 100 as indicated by the dotted and full lines, Fig. 3. If it is assumed that the wrench in Fig. 3 is in the operation of unscrewing a nut, it is to be understood that in order to screw the nut, the wrench would be inverted 105 before application to the nut, and the handle would be turned in a clockwise direction.

In order to provide a reversible or double-acting wrench there will be two pivots 4^a and 4^b , and the member 3 will have slots 5^a and 5^b through which the said pivots respectively pass. Thus, when a nut such as the pentag-

onal hydrant nut shown at 8 is embraced by the member 3 it is merely necessary to turn the handle in one direction to unscrew the nut and to open the hydrant valve, and 5 in the opposite direction to close it, without the necessity of removing and reversing the wrench, for the purpose of turning the nut in either or both directions.

When the nut is unscrewed through an 10 anti-clockwise rotation of the handle 1^a, the pivot 4^b, becomes the fulcrum upon which the handle rotates for the purpose of forcing two adjacent sides of a non-parallel sided polygonal nut, (such as shown at 8) against 15 the two adjacent walls or surfaces 6 of the nut embracing element 3. On the other hand if, without removing the wrench from the nut 8, the handle were rotated in a clockwise direction the pivot 4^a would become the 20 fulcrum and the nut would be forced against the two surfaces 6, as before, and would be turned in the direction of the handle movement.

The usual practice in opening fire plugs 25 and hydrant valves is to use a box or socket type of wrench, which, through its necessary operative looseness quickly injures the corners of the hydrant nut and becomes a dangerous implement. With the present invention 30 two adjacent sides of the hydrant nut are pressed firmly against corresponding surfaces at the same angle to each other, as the adjacent sides of the nut, thus preventing any injury to the nut even when the 35 valve is cemented to its seat through deposits, corrosion or jamming. The pressure exerted by the handle head against the nut for the purpose of forcing the two adjacent sides into firm continuous contact with the 40 surfaces of the nut embracing element is always proportional to the resistance of the nut to turning; thus insuring the faces and corners of the nut against injury.

From the foregoing description taken in 45 connection with the accompanying drawings,

the advantages of the construction and method of operation will be readily understood by those skilled in the art to which the invention appertains, and while I have described the principle of operation, together 50 with the device which I now consider to be the best embodiment thereof, I desire to have it understood that the device shown is merely illustrative, and that such changes may be made when desired as are within the scope 55 of the appended claims.

Having thus described my invention, I claim as new and desire to secure by Letters Patent:

1. A wrench comprising a handle, a head 60 on said handle the foremost periphery of said head being convexly curved throughout, a nut embracing element having a reentrant angle adapted to engage two adjacent sides of a polygonal nut said nut embracing element being pivoted to said head eccentrically thereof, the periphery of the head always contacting with the face of the nut substantially diametrically opposite the reentrant angle forcing the nut toward this point when 70 the handle is turned in either direction.

2. A wrench, comprising a handle with a nut embracing element slot and pin connected at two points to the head thereof; the nut embracing element being adapted to engage two adjacent sides of a non-parallel sided polygonal nut, the handle head contacting with a side of the nut diametrically opposite the junction of the aforesaid adjacent sides and adapted to force the nut 80 toward this point when the handle is rotated in either direction.

In testimony whereof I have signed my name to this specification in the presence of two subscribing witnesses.

WILLIAM C. BRIGHTLY.
